US00D584321S

(12) **United States Design Patent**
Matsumoto et al.

(10) **Patent No.:** US D584,321 S
(45) **Date of Patent:** ** Jan. 6, 2009

(54) **TRACTOR**

(75) Inventors: **Kunihiro Matsumoto**, Osaka (JP);
Junko Shibaoka, Osaka (JP)

(73) Assignee: **Yanmar Co., Ltd.**, Osaka (JP)

(**) Term: **14 Years**

(21) Appl. No.: **29/299,860**

(22) Filed: **Jan. 4, 2008**

(30) **Foreign Application Priority Data**

Jul. 4, 2007 (JP) 2007-18056

(51) **LOC (9) Cl.** **15-03**

(52) **U.S. Cl.** **D15/28; D15/17**

(58) **Field of Classification Search** D15/10,
D15/22-26, 28, 11, 14-17, 30, 31, 33; 180/89.1,
180/89.12, 900; 56/12.7, 15.8, 220, 76.7,
56/202, 254, 255, 297, 320.1, 320.2, 13.3,
56/13.4, 294, 20.2, 17.5, 16.7; D12/163,
D12/173

See application file for complete search history.
